UNITED STATES PATENT OFFICE

CLARENCE E. STOW, OF TULSA, OKLAHOMA

DESIGN FOR A VEHICLE SIGNAL

Application filed August 20, 1932. Serial No. 44,646. Term of patent 3½ years.

To all whom it may concern:

Be it known that I, CLARENCE E. Stow, a citizen of the United States, residing at Tulsa, in the county of Tulsa and State of Oklahoma, have invented a new, original, and ornamental Design for a Vehicle Signal, of which the following is a specification, reference being had to the accompanying drawing, forming part thereof.

Figure 1 is a rear perspective view of a vehicle signal showing my new design.

Figure 2 is a front perspective view thereof.

I claim:

The ornamental design for a vehicle signal as shown.

CLARENCE E. STOW.
